US0D1025188S

(12) **United States Design Patent** (10) Patent No.: **US D1,025,188 S**
(45) Date of Patent: ** Apr. 30, 2024

(54) **CAMERA TOP HANDLE**

(71) Applicant: **SHENZHEN NEEWER TECHNOLOGY CO. LTD**, Shenzhen (CN)

(72) Inventors: **Jun Wang**, Shenzhen (CN); **Yan Ke**, Shenzhen (CN); **Paihan Chen**, Shenzhen (CN); **Liuyin Wang**, Shenzhen (CN)

(73) Assignee: **SHENZHEN NEEWER TECHNOLOGY CO. LTD**, Shenzhen (CN)

(**) Term: **15 Years**

(21) Appl. No.: **29/888,479**

(22) Filed: **Mar. 31, 2023**

(51) LOC (14) Cl. **16-05**

(52) U.S. Cl.

USPC **D16/243**
